CLAIM

The ornamental design for an anemometer generator frame, as shown.

DESCRIPTION

FIG. 1 is a front and side isometric view of an anemometer generator frame showing my new design; FIG. 2 is a right side elevational view thereof; FIG. 3 is a vertical cross section taken along lines 3—3 of FIG. 2;

FIG. 4 is a top plan view thereof, the bottom being identical thereto;

FIG. 5 is a longitudinal cross-section taken along lines 5—5 of FIG. 4.

FIG. 1**FIG. 2****FIG. 4****FIG. 3****FIG. 5**
